(57) **CLAIM**

The ornamental design of a securing device, as shown and described.

DESCRIPTION

FIG. 1 is a perspective view of a first embodiment of the securing device;

FIG. 2 is a back view thereof;

FIG. 3 is a bottom view thereof;

FIG. 4 is a front view thereof;

FIG. 5 is a left view thereof;

FIG. 6 is a right view thereof; and,

FIG. 7 is a top view thereof.

FIG. 8 is a perspective view of a second embodiment of the securing device;

FIG. 9 is a back view thereof;

FIG. 10 is a bottom view thereof;

FIG. 11 is a front view thereof;

FIG. 12 is a left view thereof;

FIG. 13 is a right view thereof; and,

FIG. 14 is a top view thereof.
